UNITED STATES PATENT OFFICE.

FRANKLIN A. REECE, OF MANCHESTER, MASSACHUSETTS, ASSIGNOR TO THE REECE
BUTTON HOLE MACHINE COMPANY, OF BOSTON, MASSACHUSETTS, A CORPORATION
OF MAINE.

SEWING-MACHINE.

1,165,713.

Specification of Letters Patent. Patented Dec. 28, 1915.

Application filed June 27, 1913. Serial No. 776,108.

To all whom it may concern:

Be it known that I, FRANKLIN A. REECE, a citizen of the United States, residing at Manchester, in the county of Essex and 5 State of Massachusetts, have invented certain new and useful Improvements in Sewing-Machines, of which the following is a specification, reference being had therein to the accompanying drawing.

10 This invention relates to sewing machines, and more particularly to improvements in the mode of operating certain parts, and the mechanism for securing such operation.

The improvement is herein illustrated as 15 applied to the operation of the take-up of a sewing machine, and in connection with such take-up, it enables certain desirable speed variations during the cycle of the take-up operation.

20 The invention consists in the novel devices, arrangements, combinations, and other features illustrated and described herein.

First will be described one form in which 25 the invention can be embodied, and thereafter the novel features will be pointed out in the claims.

In the accompanying drawings forming a part hereof, Figure 1 is a left elevation 30 of a sewing machine, more or less conventionally illustrated, the same being partly in section, taken on the plane 1—1 of Fig. 3. Fig. 2 is a diagram showing the preferred relative operation of the needle and the 35 take-up. Fig. 3 is a rear elevation of the machine shown in Fig. 1, taken partly in section upon the plane 3—3.

Similar numerals indicate corresponding 40 parts in the different figures.

45 It is an object of this invention to accomplish the results referred to, and to give the take-up or other part of the machine, a quick advance and slow return movement by means of a shaft which has a fixed position in the machine, and carries a pin which is offset from the shaft and fitted to revolve about it, together with a link connection between the revolving pin and the take-up or part to be reciprocated.

50 The following detailed description indicates an embodiment: The general parts of the sewing machine comprise a frame or casing 9, which carries the operating parts. There will, as usual, be a main or pulley 55 shaft 10, which is shown arranged horizon-

tally and transversely. A gear 11 on the main shaft drives a pinion 12 on an auxiliary shaft 13. The shaft 13 carries a crank comprising the offset pin 14, and the side arms 15. A link 16 is shown extending 60 from the crank pin to a pivotal connection 17, at the extremity of one arm of the pivoted take-up lever, 18, which may swing about an intermediately located pivot 19. The take-up itself consists of the extreme 65 forward end of the lever 18, where there may be provided a thread eye, wheel or the like.

In order to explain the operation of the 70 described mechanism the needle operation 75 will first be referred to. On the same shaft 13 which carries the crank is an eccentric 20, whose strap 21 has a connection 22 to the rear end of a needle bar lever 23, which is connected at its forward end with a needle bar 24 carrying the needle 25. The main and auxiliary shafts 10 and 13 being assumed to rotate with uniform speed, the 80 needle and the take-up will both reciprocate upwardly and downwardly in harmony with each other.

The needle movement may be as indicated 85 in the diagram Fig. 2, wherein the curved line marked "Needle" indicates the needle and its high position at 315°, or 180° in advance of the low position. The level of 90 the work is indicated by a dotted line and it will be understood that the needle and take-up positions are inversely indicated so that the degree of descent is shown by the height of the curve at any given point.

Instead of operating the take-up to execute its take-up and return movements, each in 180°, the proposal is that the return 95 movement or descent of the take-up should be prolonged, and that the advance or take-up movement should be quickened. The advantages of such operation will be understood by those skilled in the art. The ability 100 to smoothly and efficiently take-up the thread in a very brief period of time after the needle is disengaged from the work, improves the sewing machine and enables a more satisfactory coöperation with the 105 mechanism which handles the thread beneath the work-plate.

The mechanical movement introduced herein for operating the take-up and comprising the parts 13, 14, 15, 16, 17 and 18 110

is a species of link motion, whose mode of action can be easily worked out. It is deemed unnecessary herein, however, to illustrate more than the result of the same. 5 The diagram Fig. 2 shows that the take-up passes from its highest point at zero degrees to its lowest point at approximately 232° . This slow descent or return movement is succeeded by a rapid advance or take-up 10 movement beginning at 233° and completed at 360° . The relative times of advance and return, therefore, instead of being equal are as 127 to 233. The mechanical movement which secures this valuable action would 15 also, in some cases, be applicable to the operation of the needle bar, if it were desired to vary its periods of advance and return.

It will thus be seen that there has been described a sewing machine attaining the 20 objects and advantages referred to, and embodying the principles of this improvement; and other advantages therein will be apparent to those skilled in the art.

Since matters of design, proportion, de- 25 tails and other features may be varied without departing from the principles of the improvement, no limitation is intended to such features excepting so far as specified in the appended claims.

30 What is claimed is:

1. In a sewing machine, the combination of a rotary shaft as 13, a pivoted take-up arm, a crank on said shaft and a link con-

necting said crank and arm, said crank and link both being comparatively much shorter 35 than the distance from the pivot of said arm to its point of connection to the link.

2. In a sewing machine, the combination of a rotary shaft as 13, a pivoted take-up 40 arm, a crank on said shaft and a link connecting said crank and arm, said crank and link both being comparatively much shorter 45 than the distance from the pivot of said arm to its point of connection to the link, a needle bar and connection from the shaft for reciprocating said bar; whereby the take-up is given a quick take-up movement and slow 50 return movement in harmony with the needle bar movements.

3. In a sewing machine, the combination 55 of a rotary shaft, a pivoted take-up arm of an effective length between its pivot and the link therein mentioned, nearly equal to the distance between the axes of said arm and shaft, a crank on said shaft, and a link connecting said crank and arm of an effective length nearly equal to the crank arm length and substantially shorter than said take-up arm.

In testimony whereof I affix my signature 60 in presence of two witnesses.

FRANKLIN A. REECE.
